(57) **CLAIM**

The ornamental design for a cartridge for medicine injector as shown and described.

DESCRIPTION

FIG. 1 is a left perspective view of a cartridge for medicine injector showing our new design;

FIG. 2 is a right perspective view thereof;

FIG. 3 is another left perspective view thereof;

FIG. 4 is a front view thereof;

FIG. 5 is a rear view thereof;

FIG. 6 is an enlarged left view thereof;

FIG. 7 is an enlarged right view thereof;

FIG. 8 is a top view thereof; and,

FIG. 9 is a bottom view thereof.

The broken lines shown in the drawings illustrate portions of the cartridge for medicine injector which form no part of the claimed design.

1 Claim, 3 Drawing Sheets
